28 Claims. (Cl. 105—197)

1

This invention relates to a railway car truck and more particularly to a ride control truck of quick wheel change type embodying novel friction means for dampening the vertical oscillations of the bolster.

An object of our invention is to devise a railway car truck such as that described wherein the friction means comprise a pair of friction shoes mounted in each end of the bolster with each shoe having frictional engagement with the adjacent side frame columns and wherein resilient means associated with both shoes support the same, and other resilient means independently associated with each shoe are operative to urge the shoes into frictional engagement with the columns of the side frames.

Another object of our invention is to design a truck such as that described, wherein the bolster and associated friction means may be readily disassembled from the side frames so as to accommodate a quick wheel change by elevating the bolster in the bolster opening and removing the bolster-supporting springs whereupon the bolster may be lowered in said opening and removed therefrom while the associated friction means remain in normal assembled relationship with the bolster.

In one form of our invention, we have illustrated the friction shoes as being supported on a semielliptic spring afforded a seat along the longitudinal center line of the bolster end on the bottom wall of the bolster, and in a modification of our invention the friction shoes are supported between two semielliptic springs with the springs being respectively seated on the top and bottom walls of the bolster along the longitudinal center line of the bolster and wherein in each of these forms of our invention each shoe is provided with a coil spring adapted to urge the shoe into frictional engagement with the adjacent column of the side frame. In the modification of our invention, the friction shoes are actuated into frictional engagement with the side frame columns by the coil springs to dampen relatively great oscillations of the bolster and the semielliptic springs supporting the shoes are adapted to permit small oscillations of the bolster without actuation of the friction shoes.

In the drawings:

Figure 1 is a fragmentary side elevation, partly in section, of a car truck incorporating our invention, said sectional view being taken approximately in the longitudinal vertical plane bisecting the side frame as indicated by the line 1—1 of Figure 2;

2

Figure 2 is a fragmentary top plan view of the car truck shown in Figure 1, partly in section, the view being taken approximately in the planes indicated by the line 2—2 of Figure 1 looking in the direction indicated by the arrows:

Figure 3 is a fragmentary sectional view through the bolster illustrated in Figures 1 and 2, the section being taken approximately in the longitudinal vertical plane bisecting the bolster as indicated by the line 3—3 of Figure 2;

Figure 4 is a fragmentary side elevation of the bolster and the associated friction means;

Figures 5, 6, and 7 illustrate our novel friction shoe, Figure 5 being a top plan view thereof, Figure 6 a rear elevation thereof, and Figure 7 a side elevation thereof; and

Figure 8 is a fragmentary view showing a modification of our invention, the view being comparable to that shown in Figure 1 and the left half of the view being in section along a plane like that of Figure 1.

Referring first to the preferred form of our invention illustrated in Figures 1—7, our novel car truck may comprise the side frame of well known truss type having a compression member 2, a tension member 4, and spaced columns 6, 8 merging therewith to form a central bolster opening 8 and spaced window openings 10, 10 outwardly thereof. A bolster 12 is spring-supported as at 14 from a plurality of long travel springs diagrammatically indicated at 16, 16, said springs being positioned as at 18 on the spring seat portion of the tension member and between spaced upstanding inboard and outboard flanges 20 defining said seat portion.

The end portion of the bolster 12 may be of box section, having a top wall 22, a bottom wall 24, and spaced sidewalls 26, 26, a vertical longitudinal central rib 28 having at opposite sides thereof spaced inboard and outboard transverse webs 30 and 32 defining with said top and bottom walls a friction shoe pocket 34 in each side of the bolster end.

Within each pocket 34 may be mounted a friction shoe 38 having a plane vertical face in frictional engagement as at 40 along the wear plate 42 fixed in any conventional manner on the adjacent column 6. The friction shoe in each pocket 34 is shown in Figures 5—7 and is a generally rectangular block, said shoe comprising the friction wall 44 affording a plane friction surface 46 for engagement with the adjacent side frame column. The inward side of each shoe is cored away centrally thereof to provide inboard and outboard portions 48, 48 having opposed arcu-

ate surfaces 50, 50 providing positioning means for one end of a coil spring 52 received therebetween and in abutment with the shoe, the other end of said spring bearing against the vertical central rib 28 of the bolster and receiving therewithin a boss 54 on said rib, said spring being operative to urge the shoe outwardly of the pocket 34 and the friction face 48 of the shoe into engagement with the wear plate 42 on the adjacent column. Each shoe is formed to provide an upper plane surface 56 having slidable engagement as at 58 with a corresponding surface on the bolster top wall 22, the shoes in respective pockets being urged into said engagement by a semielliptic spring 60 extending through a horizontal slot 61 in the vertical center rib 28 of the bolster and between the inboard and outboard webs 30 and 32 of each pocket, the central portion of said spring being seated on the bolster bottom wall 24 and the opposite ends thereof respectively having engagement as at 64 with a plane surface 62 on the bottom of each shoe 38, said surface 62 affording a slidable seat for the adjacent end of the spring 60. It will be apparent that, by this arrangement, the spring 60 will urge each shoe into engagement with the bolster top wall 22, as clearly shown in Figure 1, said bolster bottom wall 24 providing a seat on which the spring may fulcrum. It may be noted from a consideration of Figures 5 and 7 that the upper and lower plane surfaces 56 and 62 of each shoe are of substantial area so that sufficient bearing will be had against the bolster top wall 22 and the associated end of the spring 60.

The body portion of each friction shoe may also be cored out as at 63 to accommodate a bar or pin which may be inserted therethrough and passed through aligned openings 65, 65 in the transverse walls 30 and 32 of each bolster pocket, thus affording means of retaining the friction shoes in assembly within the bolster. The pin means (not shown) may be utilized when the snubbing means is assembled in the end of the bolster preparatory to mounting the bolster in position on the side frames. After the bolster is in position the pins may be removed permitting the friction shoes to move outwardly into engagement with the adjacent columns. The pins may also be used to disengage the bolster from the side frames for wheel change purposes by the insertion of a fulcrum bar (not shown) between one side of the bolster and the adjacent column to urge the bolster laterally of the side frame and thereby to urge the shoe on the other side of the bolster into the associated bolster pocket with the openings 63, 65, 65 in alignment for receiving the pin means, the same process being repeated at the opposite side of the bolster to move the associated shoe to a position to accommodate entrance of the pin for locking the other shoe in the opposite bolster pocket.

The bolster 12 may have the usual inboard and outboard guide lugs 66 and 68 for cooperation with the inboard and outboard guide portions of the side frame columns 8, and it will be noted from a consideration of Figure 1 that the bolster opening is provided at the lower end thereof with a widened portion 70 and that the distance between the outboard flange 20 and the guide portions of the columns is greater than the depth of the outboard guide lugs 68 of the bolster, whereupon, after retraction of the shoes in the bolster pockets as hereinbefore described and elevation of the bolster to the top of the bolster opening and removal of the springs 16, the bolster may be

lowered and removed from the side frame for effecting a quick wheel change.

A modification of our invention is illustrated in Figure 8 wherein semielliptic springs are provided both at the top and bottom of the shoes for permitting relatively small oscillations of the bolster without movement of the shoes frictionally engaged with the side frame columns during operation of the car, while permitting movement of the shoes upon greater oscillations of the bolster to afford frictional control of the bolster-supporting springs. Referring now to Figure 8, the side frame columns are identical with those previously described and are fragmentarily indicated 5 both at 102, 102 with wear plates on their inner faces at 104, 104 affording friction surfaces in engagement with respective friction shoes 106, 106. The friction shoes are substantially identical with those previously shown and described and each of 10 the shoes is received within a pocket 108 at opposite sides of the bolster 110, each pocket being defined by inboard and outboard transverse walls 112 and 114 and the top and bottom walls 116 and 118 of the bolster. The rear portion of each 15 shoe is provided with spaced side walls 120 receiving therebetween one end of the coil spring 122 for positioning the same and the opposite end of the spring is positioned on the vertical rib 124 of the bolster by the boss 125. The friction shoes 20 are supported on opposite sides thereof between the semielliptic springs 126, 126, the top spring being received within a slot 128 within the vertical longitudinal central rib 124 and seated centrally on the top wall 116 of the bolster and having the opposite ends thereof in engagement as 25 at 130 with the upper plane surface 132 on the adjacent shoe, the lower spring 126 extending through a slot 134 in the rib 124 and seating on the bottom wall 118 of the bolster with the opposite ends of the spring 126 slidably engaging the lower plane surface 136 on the adjacent shoe as 30 at 138, each of the bolster walls associated with the respective springs affording a fulcrum for the spring centrally disposed thereon. It will be apparent that the semielliptic springs 126, 126 will resiliently support the shoes therebetween and it is within the contemplation of our invention that the semielliptic springs and coil springs 122, 122 be of such relative capacity that said coil springs 35 122 will maintain the shoes in fixed engagement with the side frame columns during relatively small movements of the bolster, while the flexure of the semielliptic springs 126, 126 will be freely had to an extent that the spring 126 on each side of the shoes will flex a predetermined and appreciable extent without engagement of the top and bottom walls of the bolster with the opposite ends of the adjacent semielliptic spring 126 before the shoes will be moved in the direction of travel of the bolster, it being understood 40 that any relatively greater oscillations of the bolster will cause the springs 126, 126 to become operative to actuate the friction shoes in the direction of travel of the bolster for snubbing the harmonic oscillations of the bolster-supporting springs. It will be apparent that the semielliptic springs supporting the shoes will permit relatively small movements of the bolster without actuation of the friction shoes whereby during 45 the operation of the car, such movements will be cushioned by the bolster-supporting coil springs 16, the friction shoes only being utilized under load conditions inducing relatively great oscillations of the bolster-supporting springs for snubbing the same, thereby, in both cases, greatly im-

proving the riding qualities of the car while prolonging the useful life of the friction means.

As in the previous embodiment of our invention, the bolster is provided at opposite sides thereof with the inboard and outboard guide lugs 140 and 142 receiving the guide portions of the adjacent column therebetween, the outboard guide lugs 142 being of less depth than the widened lower portion of the bolster opening 144 for the purposes of quick wheel change as previously described, the shoes each being provided with an opening 148 adapted to receive pin means (not shown) passing therethrough and aligned openings 148, 148 in the transverse inboard and outboard walls 112 and 114 of each bolster pocket in the manner previously described for retracting the shoes in the bolster pockets during assembly and disassembly of the bolster with the side frames.

It is to be understood that we do not wish to be limited by the exact embodiments of the device shown which are merely by way of illustration and not limitation as various and other forms of the device will, of course, be apparent to those skilled in the art without departing from the spirit of the invention or the scope of the claims.

We claim:

1. In a railway car truck, a side frame comprising compression and tension members and spaced columns defining a bolster opening, said tension member comprising a spring seat with spaced inboard and outboard flanges, a plurality of springs on said seat and confined between said flanges, a bolster supported on said springs in said opening, said bolster having a box section end portion with top and bottom walls and spaced transverse webs merging therewith and defining a pocket in each side thereof and a central rib extending between said walls, spaced openings in said rib adjacent respective walls, friction shoes in said pockets, a semi-elliptic spring fulcrumed centrally of each of said walls in the adjacent opening, said springs having the opposite ends thereof slidably receiving said shoes therebetween for supporting the same, and resilient means compressed between said shoes and said central rib for urging said shoes into engagement with said columns.

2. In a railway car truck, a side frame comprising compression and tension members and spaced columns defining a bolster opening, said tension member comprising a spring seat with spaced inboard and outboard flanges, a plurality of springs on said seat and confined between said flanges, a bolster supported on said springs in said opening, said bolster having a box section end portion with top and bottom walls and spaced transverse webs merging therewith and defining a pocket in each side thereof and a central rib extending between said walls, spaced openings in said rib adjacent respective walls, friction shoes in said pockets, a semi-elliptic spring fulcrumed centrally of each of said walls in the adjacent opening, said springs having the opposite ends thereof slidably engaging opposite sides of said shoes, and resilient means compressed between said shoes and said central rib for urging said shoes into engagement with said columns.

3. In a railway car truck, a side frame comprising compression and tension members and spaced columns defining a bolster opening, said tension member comprising a spring seat with spaced inboard and outboard flanges, a plurality of springs on said seat and confined between said flanges, a bolster supported on said springs in

5 said opening, said bolster having a box section end portion with top and bottom walls and spaced transverse webs merging therewith and defining a pocket in each side thereof and a central rib extending between said walls, an opening in said rib adjacent said bottom wall, friction shoes in said pockets, a semi-elliptic spring fulcrumed centrally from said bottom wall in said opening and having the opposite ends thereof slidably supporting said shoes, and resilient means compressed between said shoes and said central rib for urging said shoes into engagement with said columns.

4. In a railway car truck, a side frame comprising spaced columns partly defining a bolster opening, a relatively movable bolster resiliently supported on said frame in said opening, said bolster having a box section end portion with top and bottom walls and spaced transverse webs merging therewith and defining a pocket in each side thereof, and a central rib extending between said walls, said rib comprising spaced openings therein adjacent respective walls, friction shoes in said pockets, a resilient member fulcrumed centrally of each of said walls in the adjacent opening, said members having the opposite ends thereof receiving said shoes therebetween and slidably supporting the same, and resilient means compressed between said shoes and said central rib for urging said shoes into frictional engagement with said columns, said resilient means and said resilient members having variable capacities whereby said shoes are movable with said columns relative to said bolster during relatively small oscillations of said bolster and movable with said bolster relative to said columns during relatively great oscillations of said bolster.

5. In a railway car truck, a side frame having tension and compression members and spaced columns defining a bolster opening, a bolster spring-supported from said tension member in said opening, said bolster having a box section end portion with spaced top and bottom walls and transverse webs defining a pocket in each side of said bolster and a central rib between said pockets, an opening in said central rib, friction shoes in said pockets, a resilient member fulcrumed centrally of said bolster in said opening and having opposite ends thereof respectively engaging said shoes and operatively urging the same into engagement with one of said walls, and coil springs compressed between said shoes and said central rib and operative to urge said shoes into frictional engagement with the adjacent column.

6. In a railway car truck, a side frame comprising spaced columns partly defining a bolster opening, a bolster resiliently supported on said frame in said opening, said bolster having a box section end portion with top and bottom walls and spaced transverse webs merging therewith and defining a pocket in each side thereof and a central rib extending between said walls, said rib comprising an opening therein, friction shoes in said pockets in slidable engagement with one of said walls, a resilient member fulcrumed centrally of said bolster in said opening and having opposite ends thereof engaging respective shoes and operatively urging the same into engagement with the associated wall, and resilient means compressed between said shoes and said central rib and operative to urge said shoes into engagement with the adjacent columns.

7. In a railway car truck, a side frame having spaced columns partly defining a bolster opening, a relatively movable bolster spring-supported on

said frame in said opening and friction means mounted in the end of said bolster for engagement with said columns, said friction means comprising friction shoes pocketed in said bolster, and resilient members fulcrumed centrally thereof from said bolster and having adjacent opposite ends thereof in said pockets for slidably supporting the friction shoes therebetween, and resilient means compressed between said shoes and operative to urge the same into frictional engagement with the adjacent column walls, said resilient means and members being so formed and arranged that relatively small oscillations of said bolster effect deflection of said resilient members without actuation of said shoes.

8. In a railway car truck, a side frame having spaced columns partly defining a bolster opening, a bolster spring-supported on said frame in said opening and friction means mounted in the end of said bolster for engagement with said columns, said friction means comprising friction shoes pocketed in said bolster, and resilient members fulcrumed centrally thereof from said bolster and having adjacent opposite ends thereof in said pockets for slidably supporting the friction shoes therebetween, and resilient means compressed between said shoes and operative to urge the same into engagement with the adjacent column walls, said resilient members and said resilient means having variable capacities whereby relatively small oscillations of said bolster are ineffective to cause sufficient movement of said resilient members for actuation of said shoes.

9. In a railway car truck, a supporting member having spaced columns defining an opening therein, a supported member spring-supported in said opening, said supported member having a box-section end portion with top and bottom walls and spaced transverse webs defining a pocket in each side thereof, a central rib extending between said walls intermediate said pockets and having an opening therein, a resilient member fulcrumed centrally of said supported member in said last-named opening and having opposite ends thereof received within respective pockets, a friction shoe in each pocket slidably seated on the adjacent end of said resilient member, and resilient means compressed between each shoe and said central rib and operative to urge said shoes into engagement with the adjacent columns.

10. In a railway car truck, a side frame having spaced columns partly defining a bolster opening, a bolster spring-supported on said frame in said opening, and friction means mounted in the end of said bolster for engagement with said columns, said friction means comprising friction shoes pocketed in said bolster and in slidable engagement with a wall thereof, a resilient member fulcrumed intermediate its ends from a wall of said bolster spaced from said first-mentioned wall and urging said shoes into engagement with the adjacent wall, and resilient means compressed between said shoes and operative to urge said shoes into engagement with the adjacent columns.

11. In a railway car truck, a side frame comprising spaced columns partly defining a bolster opening, a bolster resiliently supported on said frame in said opening, said bolster having a box-section end portion with top and bottom walls and spaced transverse webs merging therewith and defining a pocket in each side thereof and a central rib extending between said walls, said rib comprising spaced openings therein adjacent respective walls, friction shoes in said pockets, a resilient member fulcrumed centrally of each

8
of said walls in the adjacent opening, said members having the opposite ends thereof receiving said shoes therebetween and slidably supporting the same, and resilient means compressed between said shoes and said central rib for urging said shoes into engagement with said columns.

12. In a railway car truck, a side frame having spaced columns partly defining a bolster opening, a bolster spring-supported on said frame in said opening, and friction means mounted in the end of said bolster for engagement with said columns, said friction means comprising friction shoes pocketed in said bolster, a resilient member fulcrumed centrally thereof from said bolster at opposite sides of said shoes, said resilient members having the adjacent opposite ends thereof slidably supporting therebetween the shoe in each pocket, and resilient means compressed between said shoes and operative to urge the same into engagement with the adjacent columns.

13. In a railway car truck, a side frame having spaced columns partly defining a bolster opening, a bolster spring-supported on said frame in said opening, and friction means mounted in the end of said bolster for engagement with said columns, said friction means comprising friction shoes pocketed in said bolster, spaced resilient members fulcrumed centrally thereof from said bolster and having the adjacent ends thereof slidably supporting the shoe in each pocket, and resilient means between said members engaging said shoe for urging the same into engagement with the adjacent columns.

14. In a railway car truck, a side frame having spaced columns partly defining a bolster opening, a bolster spring-supported on said frame in said opening, and friction means mounted in the end of said bolster for engagement with said columns, said friction means comprising friction shoes pocketed in said bolster, a resilient member fulcrumed intermediate the ends thereof from said bolster and operatively urging each shoe into slidable engagement with a wall of the associated pocket, and resilient means compressed between said shoes and operative to urge the same into engagement with the adjacent column.

15. In a railway car truck, a side frame having spaced columns partly defining a bolster opening, a bolster spring-supported on said frame in said opening, and friction means mounted in the end of said bolster for engagement with said columns, said friction means comprising friction shoes pocketed in said bolster and in slidable engagement with a wall thereof, a resilient member fulcrumed intermediate its ends from said bolster and urging said shoes into engagement with the adjacent wall, and resilient means compressed between said shoes and operative to urge said shoes into engagement with the adjacent columns.

16. In a railway car truck, a side frame comprising spaced columns defining a bolster opening, a bolster supported on said frame in said opening and having an end with pockets therein, friction means in said pockets, said friction means comprising spaced shoes in engagement with the adjacent columns, resilient means extending transversely of said bolster and within respective pockets for supporting the shoes therein, and other resilient means for actuating said shoes into engagement with said columns.

17. A bolster having a box-section end portion comprising spaced top and bottom walls and spaced transverse webs merging therewith and

9

defining aligned openings at opposite sides of said bolster, a central rib extending between said walls having an opening adjacent one of said walls for receiving a resilient member afforded a fulcrum seat on said one wall, the other of said walls presenting adjacent opposite sides thereof coplanar seats for associated friction shoes.

18. In a railway vehicle, a supporting member having spaced vertical columns, a supported member spring-supported on said first-mentioned member between said columns, friction shoes pocketed in said supported member at opposite sides thereof and slidably seated on substantially horizontal surfaces thereof, a resilient member fulcrumed intermediate its ends on said supported member and urging each shoe into engagement with its associated surface, and resilient means compressed between said shoes and operative to urge said shoes into engagement with said columns.

19. In a railway vehicle, a supporting member having spaced vertical columns, a member spring-supported from said first-mentioned member between said columns and having lateral pockets aligned with said columns, friction shoes in said pockets, a resilient element fulcrumed in said supported member and operative to urge each shoe against a substantially horizontal surface on said supported member, and resilient means compressed between said shoes and operative to urge said shoes along said surfaces outwardly of said supported member into engagement with said columns.

20. In a railway vehicle, a supporting member having spaced vertical friction surfaces, a member spring-supported from said first-mentioned member between said surfaces and comprising a substantially horizontal face adjacent each surface, friction elements seated against respective surfaces, a resilient member fulcrumed from said supported member and operative to urge said shoes against respective faces, and resilient means compressed between said elements and operative to urge the same along said faces into frictional engagement with said surfaces.

21. In a railway vehicle, a supporting member having spaced vertical columns, a member spring-supported on said first-mentioned member between said columns with lateral pockets aligned with said columns, friction shoes in said pockets, spaced resilient members fulcrumed centrally thereof from said supported member and having adjacent ends thereof supporting the shoes in respective pockets, and resilient means intermediate said resilient members and compressed between said shoes for urging the latter into engagement with said columns.

22. In a railway car truck, a supporting member having spaced vertical friction surfaces, a relatively movable member spring-supported between said surfaces, friction shoes carried by said supported member adjacent respective surfaces, resilient elements and means mounted on said supported member for movement therewith relative to said supporting member, said resilient elements slidably engaging said shoes therebetween in spaced relation to said supported member, and said resilient means being disposed intermediate said elements and compressed between said shoes for operatively urging the latter into frictional engagement with said surfaces, said resilient elements and means having variable capacities whereby relative movement of said members is effective to move said shoes along said surfaces only after sufficient deflec-

tion of said elements to overcome the initial frictional resistance to said movement between said shoes and surfaces induced by said resilient means.

23. In a railway car truck, a supporting member having spaced vertical friction surfaces, a relatively movable member spring-supported between said surfaces, friction shoes carried by said supported member adjacent respective surfaces, resilient elements and means within said supported member and movable therewith relative to said supporting member, said resilient elements positioning said shoes therebetween in spaced relation to said supported member and said resilient means being disposed intermediate said elements and compressed between said shoes for operatively urging the latter into frictional engagement with said surfaces, said resilient elements and means having variable capacities whereby said shoes are movable along said surfaces upon relative movement of said members inducing a sufficient variation of the capacities of said resilient elements to overcome the initial frictional resistance to said movement between said shoes and surfaces by said resilient means.

24. In a railway car truck, a supporting member having spaced vertical friction surfaces, a relatively movable member spring-supported between said surfaces, friction means carried by said supported member, said friction means comprising friction shoes adjacent respective surfaces, resilient elements above and below each shoe and compressed between said shoe and said supported member, resilient means compressed between said shoes and operative to urge said shoes into engagement with said surfaces, said resilient elements and means having variable capacities whereby relative movement of said members is effective to move said shoes along said surfaces only after deflection of said elements to overcome the initial frictional resistance to said movement between said shoes and surfaces induced by said resilient means.

25. In a railway car truck, a supporting member having spaced vertical friction surfaces, a relatively movable member spring-supported between said surfaces, friction means carried by said supported member, said friction means comprising friction shoes adjacent respective surfaces, and a plurality of resilient elements clasping and supporting said shoes in spaced relation to said supported member and compressed between said shoes and operative to urge said shoes into engagement with said surfaces, said resilient elements having variable capacities whereby said shoes are movable along said surfaces upon relative movement of said members inducing a sufficient variation of the capacities of said supporting elements to overcome the initial frictional resistance to said movement between said shoes and surfaces by said compressed elements.

26. In a railway car truck, a supporting member having spaced vertical friction surfaces, a relatively movable member spring-supported between said surfaces, friction means carried by said last-mentioned member, said friction means comprising a friction shoe adjacent each surface, vertically spaced resilient members receiving said shoe therebetween and compressed between the same and the adjacent portions of said supported member, and resilient means between said shoes and operative to urge the same into frictional engagement with said surfaces, said

11

resilient members and means having variable capacities whereby said shoes are maintained in their initial engaged positions with said surfaces by said resilient means during relative movement of said members to an extent necessary to vary the capacities of said resilient members to overcome the frictional resistance afforded by said shoes and surfaces to said movement.

27. In a railway car truck, a supporting member having spaced vertical friction surfaces, a relatively movable member spring-supported between said surfaces, friction means carried by said last-mentioned member, said friction means comprising a friction shoe adjacent each surface, vertically spaced resilient members receiving said shoe therebetween and compressed between the same and the adjacent portions of said supported member, and resilient means between said shoes and operative to urge the same into frictional engagement with said surfaces.

28. In a railway car truck, a supporting member having spaced vertical friction surfaces, a relatively movable member spring-supported between said surfaces, friction means carried by

12
said last-mentioned member, said friction means comprising a friction shoe adjacent each surface, resilient means supporting said shoes therebetween and compressed between said shoes and said supporting member, and independent resilient means compressed between said shoes and operative to urge the same into frictional engagement with said surfaces.
